(57) **CLAIM**

The ornamental design for a battery charger casing, as shown and described.

DESCRIPTION

FIG. 1 is a left side elevational view of a battery charger casing showing my new design mounted within a model motorcycle frame;

FIG. 2 is another left side elevational view of a battery charger casing showing my new design;

FIG. 3 is a rear elevational view of a battery charger casing showing my new design;

FIG. 4 is a top plan view of a battery charger casing showing my new design; and,

FIG. 5 is a right side elevational view of a battery charger casing showing my new design.

The model motorcycle frame is shown in broken lines for illustrative purposes only and forms no part of the claimed invention.
